SPARK PLUG CONSTRUCTION

Earl W. Meyer, Jr., and George E. Spaulding, Jr., Toledo, Ohio, assignors to The Electric Auto-Lite Company, Toledo, Ohio, a corporation of Ohio

Application November 29, 1957, Serial No. 699,710

4 Claims. (Cl. 313—124)

This invention relates to electrical spark discharge devices and more specifically to spark plugs incorporating very stable means for isolating the voltage source from the firing gap of the spark plug while the voltage builds up to a predetermined amount as well as making a high frequency voltage with respect to the voltage applied to the firing gap of the spark plug out of the conventional ignition coil. This application is a continuation, in part, of our application Serial No. 652,597, filed April 12, 1957.

The invention comprehends a spark plug including a very consistent auxiliary spark gap located within the insulator in circuit with the spark plug firing gap for controlling the electrical discharge of the latter until the firing or secondary voltage of the ignition system has reached a predetermined potential.

The invention contemplates a spark plug including a spark intensifier of extremely stable characteristics for isolating the voltage source of an ignition system while the voltage builds up to the predetermined amount from the firing gap of the spark plug, thereby insuring the electrical discharge notwithstanding the fact that the firing gap of the plug is fouled or shunted by a comparatively lower resistance across the electrodes by carbon deposits or other deleterious matter.

The invention comprises a spark plug provided with an extremely stable auxiliary gap vented to the atmosphere positioned within the insulator and in series with the firing gap of the spark plug, whereby the electrical discharge of the firing gap of the spark plug is consistently secured, although the spark plug may be fouled by carbon deposit or other foreign or deleterious matter.

The invention embraces a spark plug including a spark intensifier of extremely stable characteristics which performs the dual function of isolating the voltage source from the firing gap of the spark plug while the voltage builds up, as well as making a high frequency system out of the conventional ignition system.

This invention also includes a spark plug having a spark intensifier provided with an "electrical floating" conducting member arranged to bridge the gap between the electrodes without direct connection therewith and separated therefrom by a thin partition having a dielectric constant higher than air.

According to the foregoing summary of the invention indicating the general nature and substance, its main objective is to provide electrical spark discharge devices for igniting fuel mixtures including means and their arrangement for isolating the voltage source from the firing gap of the device while the voltage builds up, as well as making high frequency systems out of conventional ignition systems.

The conventional spark plugs now in use have been entirely unsatisfactory for prolonged applications in electrical circuits of ignition systems for internal combustion engines due to the fact that the spark plug becomes fouled or its firing gap becomes shunted by comparatively lower resistance due to carbon deposits or other deleterious

2

matter. This is particularly true in connection with overhead valve engines having comparatively high compression ratios wherein the firing gap of the spark plug is not isolated from the voltage source, as in such cases the condition of the firing gap is one of the main controlling factors in the voltage build-up, and thereby the fouling or the shunting of the firing gap of the spark plug prevents the building up of the voltage to a proper value for obtaining a reliable spark.

It is one of the principal objects of the invention to overcome and cure the failures and drawbacks hereinbefore enumerated by the utilization of a spark plug having a spark intensifier which performs the dual function of isolating the voltage source from the firing gap of the plugs while the voltage builds up, as well as making a high frequency voltage source out of the conventional ignition coil. Thus, the combined action of this dual function acts to build a reservoir or store energy in the distributed capacity of the coil, circuit components and wiring harness, and then discharge this stored energy very quickly and at high frequency across the gap of the intensifiers and the firing gap of the spark plugs irrespective of the presence of a comparatively low resistance path shunting the firing gaps.

Another object of the invention is to provide a spark plug having a very consistent auxiliary gap incorporating an "electrically floating" conducting means supported by a dielectric body whereby the electrical field, due to the application of voltage to its spaced electrodes of the auxiliary gap, causes rapid ionization furnishing free electrons radiating into said gap to thereby produce an electrical discharge at consistent and predictable voltage, whereby not only the spark intensifier has a low impulse ratio but the firing gap of the spark plug has practically no time lag.

Another object of the present invention is to provide an extremely stable spark intensifier integrally formed in a spark plug whereby the voltage required to produce an electrical discharge across the intensifier and a fouled spark plug gap will be more consistent and thus lower than the voltage required wherein conventional intensifiers are used with spark plugs.

Another object of this invention is to provide a spark plug having a very consistent auxiliary spark gap in which a conducting metallic band is carried on the outside of a member having a section of minimum thickness consistent with its insulating strength and which has a dielectric constant higher than air contacting the electrodes, and wherein said conducting band is dimensioned to extend the length of the gap separating the electrode overlapping their firing tips, whereby rapid ionization of the space between the electrode is consistently obtained.

A further object of the invention is to provide a spark plug having an extremely stable spark gap intensifier as a component of its non-grounded electrode, the spark intensifier being of the non-sealed type and having its spaced electrodes interconnected by an insulating body of high dielectric constant operable to provide a surface sparking gap, thus eliminating objectionable electrode pitting which made conventional devices ineffective after short operating periods.

Another object of the invention is to provide a spark plug having a spark intensifying means provided with a preionizing electrode which is solely capacitively coupled to the main arcing electrodes in a wireless, non-inductive, and resistless manner, whereby the electrical discharges across the gap of the spark intensifier are secured at a break-down voltage of comparatively low value which is predictable and consistent.

Another object of the invention is to provide a spark plug incorporating a composite electrode which includes a non-sealed auxiliary spark gap having a preionizing

electrode which is only capacitively coupled and structurally associated with each of the arcing electrodes solely by electrical insulating material defining the sparking chamber and which provides spacer means for the preionizing electrode, whereby arcing will not occur between either of the arcing and preionizing electrode as the latter is positioned outside of the sparking area.

A further object of the invention is to provide a spark plug incorporating an integrally-formed spark intensifier of utmost simplicity which broadly comprises three components; first, spaced electrodes having their discharge or vulnerable surfaces made of high melting point metals or of high erosion-resistant conducting materials without sharp edges; second, a body having a dielectric constant at least higher than air and of a very thin cross-section consistent with its insulating qualities intervening between the electrodes and in contact therewith to form, in effect, a surface sparking gap; and, third, and last component, a conducting "electrically floating" member spaced or separated from the electrodes by said dielectric body and dimensioned to over extend or bridge the length of the surface sparking gap. In carrying the present invention to practice, as shown in the embodiment herein disclosed, and consistent with economical manufacture, the dielectric body constituting the second component also performs the function of a housing or main support for the other components of the spark gap.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Referring to the drawings:

Fig. I shows a cross-sectional view of a spark plug constructed in accordance with the principles of the invention in association with a conventional ignition system;

Fig. II is an enlarged cross-sectional view on an enlarged scale of the spark intensifier shown in Fig. I.

The present invention may be incorporated in any suitable type of ignition systems and devices for producing electrical discharges to ignite combustible mixtures and for practical application of its principles, the same is illustrated in the drawings as embodied in spark plugs for use with an ignition system for internal combustion engines. However, it is to be understood that the invention is not limited in its application to the particular form shown but that it is contemplated that the principles of the invention may be used whenever the same may be found to be applicable.

Referring to the drawings, and particularly to Fig. I, the embodiment of the invention therein illustrated by way of example shows an ignition system including a spark plug comprising a hollow base or a tubular metallic shell 10 provided at its lower end with an outer threaded section 12 and having an outer polygonally-shaped upper section 13 for removably mounting the spark plug in the cylinder block of an internal combustion engine, not shown. The interior surface of the tubular shell has a reduced lower portion having an inclined annular ledge 14 providing a seat for a sealing gasket 15 adapted to be pressed into engagement with a shoulder 16 of the central enlarged portion 17 of the insulator member 18 whereby the latter is retained in sealed relation by spinning the upper ledge or lip 19 of the shell 10 against a compressible ring 20 forced thereby into engagement with the upper shoulder 21 of the insulator.

In the construction shown, to insure a gas-tight relation between the insulator member 18 and the shell 10 throughout the heat operating range of the spark plug, the shell 10 is formed with a reduced portion 23 which

is collapsed by the application of heat and pressure during assembly to effectively maintain thereafter the insulator 18 and the shell 10 in a gas-tight relation, thereby avoiding leakage in the firing chamber of the engine with which the spark plug is associated.

The insulator body 18 which is made of suitable ceramic materials bonded together, preferably of a composition including as its major component aluminum oxide, has a stepped longitudinal bore for retaining a composite electrode including a lower section or stem 24 projecting from its lower end and constituting the firing tip 25 terminating in close proximity to the end of the coaxing firing electrode 26 carried by the lower portion of the shell 10, thereby forming the firing gap 27 of the spark plug. The metallic stem 24 is provided at its upper end with an enlarged portion or head 28 providing a mechanical interlock with the lower shoulder 29 of the insulating bore, which, by suitable sealing means, forms thereby a hermetic seal, herein illustrated, in the form of a fused glass member 30. The seal member 30 is traversed by a metallic pigtail 31 permanently attached by one end to the head 28 and has its upper end 32 projecting into the bore of the insulator beyond the terminus of the glass sealing body 30. The upper end 32 of the pigtail 31 serves as connector or terminal means for the lower end 34 of the helical spring member 35 freely mounted in the enlarged section 36 of the insulator bore. The spring 35 is arranged as circuit conducting means to urge the spark intensifier of the invention 40 or auxiliary spark gap in engagement with the planar bottom surface 39 of the top hollow metallic section 38 of the composite electrode of the spark plug. The section 38 has threaded engagement with the inner walls of the enlarged portion 36 of the bore of the insulator, which section 35 provides an elongated chamber on the portion of the insulator located outside of the shell. Thus the hollow member 38 performs the dual function of terminal post for the ungrounded composite electrode and air vent means for the elongated section 36 of the bore of the insulator.

The terminal post 38 of the spark plug ungrounded electrode is in circuit through the conductor 41 to a high tension terminal of a conventional eight cylinder engine distributor, which is shown in circuit with the rotor member 43, in turn, connected by lead 45 to the high voltage potential source provided by the secondary winding 46 of an ignition coil. The secondary winding has its other end interconnected with the end 47 of the primary winding 48 of the ignition coil, and both ends are in circuit by suitable connections, including switching means 49, with a terminal of a primary source of potential such as the storage battery 50 which has its other terminal grounded as at 51 to provide a common return for the flow of current thereto. The other end 52 of the primary winding 48 is connected to make and break contacts 53-54, the latter grounded as at 56. A suitable condenser 57 is connected across the contacts 53-54, in the conventional manner. The contacts 53-54 are actuated in timed relation with the engine by means of a timing cam 58, which rotates in synchronism with the rotor 43 of the distributor 42 by a suitable mechanical connection shown diagrammatically by dotted lines 59. The separation of contacts 53-54 by the cam 58 will cause the interruption of the current energizing the primary winding 48 of the ignition coil and cause the build up of voltage or firing potential provided by the secondary winding 46 of the ignition coil to the spark plug terminal 38 to produce a jump spark or electrical discharge across the spark intensifier 40 and the firing gap 27 of the spark plug when such built up voltage reaches a predetermined amount.

An important feature of this invention is the provision of a spark plug construction incorporating as an integral component, extremely stable means for isolating the potential source from the firing gap of the spark plug while the voltage builds up to a predetermined amount as well

as making out of the conventional ignition coil a high frequency source for the voltage that is applied to produce the jump spark across the firing gap of the spark plug.

In the embodiment of the invention illustrated, the isolating means which perform the functions before enumerated are in the form of a spark intensifier 40 which broadly includes three components: first, spaced electrodes; second, a body having a high dielectric constant, at least higher than air, of a very thin cross-section consistent with its insulating quality intervening between the electrodes in contact therewith to form, in effect, a surface sparking gap; and the third and last component, a current-conducting member spaced or separated from the electrodes by said dielectric body and dimensioned to over extend or bridge the length of said surface sparking gap. In the embodiment of the invention, and as particularly shown in Fig. II, the dielectric body constituting the second component performs two functions; first, as means for decreasing and making consistent the break-down potential required to produce a rapid jump spark across the electrodes and; second, as a support and housing for the other components of the spark intensifier. As particularly shown in Fig. II, the numeral 60 designates a rigid perforated shell or hollow housing having an axial bore centrally located forming an open-ended tubular enclosure of comparatively thin wall section.

According to the principles of the invention, the housing 60 is made of a material having a dielectric constant at least higher than air and of suitable insulating characteristics to provide a surface or a spacer of minimum thin cross-section intervening between the discharge surfaces of the spaced electrodes.

In carrying the invention to practice, it has been found advantageous to make or form the housing from suitable ceramic insulating materials, including porcelain whose dielectric constant is considerably higher than air, so that the housing walls are of a minimum cross-section consistent with its insulating qualities. The housing 60 is dimensioned and arranged to support the electrodes 62 and 63 by direct engagement therewith and maintain them apart in fixed position within its axial bore by having a close fit therewith, so that accurate spacing or a non-conducting gap of predetermined length is provided. In this embodiment of the invention, the inner surface of the tubular housing 60, and particularly the thin section thereof intervening between the spaced electrodes 62 and 63, operates to form, by intercommunication therewith, a surface sparking gap 61 bridging, in effect, the non-conducting gap.

Each of the electrodes 62 and 63 is, for ease of manufacture, shown as a duplicate composite structure which, in each case, is pierced at its central portion forming respectively tubular sections 64 and 65. These tubular sections have, at their respective ends, enlarged heads 66 and 67 dimensioned to co-extend and be in alignment with the outer periphery of the tubular housing 60, forming thereby external terminals or connecting plates 69 and 70 for the spaced electrodes. The inner end of the respective tubular sections 64 and 65 are capped by ring-like or annular members 73 and 74 which constitute the other component of the electrode structure and may be termed as its vulnerable end or discharge surface. The tubular sections 64 and 65 of the electrodes 62 and 63 are dimensioned to provide a relatively large mass and are preferably made of a base metal or material having good thermal and electrical conductivity not readily oxidizable by electrical discharges.

The vulnerable components 73 and 74 of the composite electrodes 62 and 63 are fixed or carried in direct electrical contact with the ends of the corresponding tubular sections 64 and 65 by having their rear surfaces brazed or welded thereto, and are shaped and di-

dimensioned so that their surfaces are in intimate contact with the bore of the housing 60.

The annular members 73 and 74 are preferably formed and arranged, so that their discharge faces are uniplanar and rounded off at their outer periphery, as at 76 and 77 respectively, thus avoiding sharp edges or square corners adjacent to the surface gap 61, thus providing co-planar flat sections spaced adjacent to each other in substantially parallel relation and have their ends adjacent to the central bore rounded off as at 78 and 79 respectively. The vulnerable sections 73 and 74 of the composite electrode structures are preferably made of good erosion-resistant, conducting materials, or of metals having a high melting point. In carrying the invention to practice, it has been found highly advantageous to form each one of the members 73 and 74 of either tungsten, molybdenum, tantalum, or alloys of such metals. However, it is contemplated that other materials having the characteristics before mentioned may be used.

In the form of the invention disclosed, the means to enhance the rapid ionization of the space between the electrodes for decreasing the time lag of the electrical discharge, as well as controlling and stabilizing the breakdown voltage of the intensifier spark gap, are shown in the form of an electrically floating metallic band 81 surrounding or embracing the electrodes but not physically connected to either. The band 81 in the form shown is coaxial with the electrodes and is separated therefrom by being supported by the housing 60 by having direct engagement with its outer surface 82. The band 81 is preferably made of a homogeneous conducting substance which is illustrated in the form of a flat metallic ring surrounding the electrodes and being dimensioned, so that its length is somewhat greater than the length of the space separating the electrodes, so that the outer ends 84 and 85 of the band 81 extend beyond a slight distance and thereby overlap a portion of the area of members 73 and 74, as can be seen by a perusal of Fig. II.

The conducting member 81, which, in accordance with the principles of the invention in the form shown, depicts the means to reduce the impulse ratio of the intensifier spark gap and makes possible a fairly low and consistent potential to cause an electrical discharge is symmetrically placed to bridge the surface gap 61 with its outer ends 84 and 85 properly spaced from the enlarged sections 66 and 67 of the electrode structure so that flash-over will not occur or precede the electrical discharge between the discharge surfaces 83 and 84. In carrying the invention into practice, it has been found that the space separating the outer surfaces 84 and 85 of the conducting band with respect to the co-adjacent enlarged sections 66 and 67 of the electrodes should be at least more than one-half of the length of the space separating the discharge surfaces 73 and 74, in order to avoid flash-overs therebetween. It has been found by experience, based on comparative tests, that the coaxial separation or radial spacing of the electrical floating body 81 with respect to the electrode significantly affects its function as a controlling factor in reducing the impulse ratio of the spark gap and the consistency of its break-down voltage. In view of this fact, the walls of the housing 60 should be of a minimum cross-section consistent with the strength, as well as the insulating characteristics, of the dielectric material from which the same is made.

The length of the dielectric tubular section forming the housing 60 should be correlated with respect to the dimension of the gap 61 and the length of member 81, so that flash-overs between the conducting member 81 and the electrode terminals 69 and 70 will not occur or precede the jump spark across the discharge surfaces 73 and 74 of the spark intensifier 40. The conductor body 81 in this form of the invention is preferably pro-

duced by spraying or depositing upon the external surface 82 a non-insulating substance to provide a substantially uniform and homogeneous layer of metal or other current-conducting material.

Consistent with economical manufacture, it has been found that depositing a layer of silver in solution upon the external surface 82 of the tubular section of the dielectric support 60, and thereafter bonding or fusing the same thereto by the application of heat, produces a very effective electric floating metallic member at low cost in very close proximity to the electrodes having intimate contact with the outer surface 82 of the housing 60.

Comparative tests indicate that, while maximum effectiveness is obtained by providing the electrical floating member of the invention totally encircling the electrodes, the stability of the gap is not materially impaired when such electrical floating member is circumferentially reduced to 180 degrees. However, it has been determined that further circumferential reduction tends to decrease its effectiveness and thereby its regulating function as a stabilizing and reduction factor for the break-down voltage of the gap. Moreover, it has been found that reduction of the length of the electrical floating member has a tendency to increase the break-down potential for a given gap spacing when such reduction in length does not provide a satisfactory bridging of the gap.

It should be noted that the actual dimensions of the component elements of the embodiment of the invention illustrated in Fig. II have been materially exaggerated for sake of clarity, being approximately five times the actual dimensions of the device.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirement of the prior art.

What is claimed:

1. A spark plug comprising a metallic shell, an insulator having a portion mounted in sealed relation within said shell, a central bore transversing said insulator, a composite main electrode located in said bore, a metallic member sealed to said bore forming the lower component of said composite electrode, said metallic member having one end projecting from the lower end of said insulator, a second primary electrode carried by said shell in spaced relation with the end of said member forming thereby the firing gap of the spark plug, the upper component of said main electrode formed by a pierced conducting member projecting at the upper end of said bore for subjecting the other components of the main electrode to the atmosphere, pierced secondary electrodes having their discharge faces spaced apart to provide a predetermined sparking space subjected to the atmosphere forming thereby an auxiliary spark gap in series with the firing gap of the spark plug, a tubular insulating member having a high dielectric constant directly contacting the outer surfaces of the discharge faces of the secondary electrodes to change thereby the predetermined sparking space into a surface sparking gap, and a current-conducting member carried by the outer surface of said tubular insulating member in a non-conductive relation to the secondary electrodes, constituting thereby an electrically floating conducting member in respect thereto, said current-conducting member having a length dimensioned and arranged to bridge in a non-conductive relation the said surface sparking gap.

2. A spark plug comprising a metallic shell, an insulator having a portion mounted in sealed relation within said shell and its upper portion projecting therefrom, a central bore transversing said insulator forming an elongated chamber on the upper portion of said insulator, a composite main electrode located in said bore, a metallic stem sealed to said bore forming the lower component of said composite electrode, said metallic stem having one end projecting from the lower end of said insulator, a second primary electrode carried by said shell in spaced relation with the end of said stem forming thereby the firing gap of the spark plug, the upper component of said main electrode formed by a conducting member closing the upper end of said elongated chamber, said conducting member pierced for subjecting the said elongated chamber to the atmosphere, perforated secondary electrodes having uniplanar discharge faces spaced apart to provide a predetermined sparking space subjected to the atmosphere forming in said elongated chamber an auxiliary spark gap in series with the firing gap of the spark plug, a tubular insulating member having a high dielectric constant directly contacting the outer periphery of the discharge faces of the secondary electrodes to change thereby the predetermined sparking space into a surface sparking gap, and a current-conducting band carried by the outer surface of said tubular insulating member in a non-conductive relation to the secondary electrodes, constituting thereby an electrically floating conducting band in respect thereto, said current-conducting band dimensioned and arranged to bridge and encircle in a non-conductive relation the said surface sparking gap.

3. A spark plug comprising a metallic shell, an insulator having a portion mounted in sealed relation within said shell, a central bore transversing said insulator, a composite main electrode located in said bore, a metallic member sealed to said bore forming the lower component of said composite electrode, said metallic member having one end projecting from the lower end of said insulator, a second primary electrode carried by said shell in spaced relation with the end of said member forming thereby the firing gap of the spark plug, the upper component of said main electrode formed by a perforated conducting member projecting at the upper end of said bore for subjecting the other components of the main electrode to the atmosphere, perforated secondary electrodes having co-planar discharge faces spaced apart to provide a predetermined air sparking space subjected to the atmosphere forming thereby an auxiliary spark gap in series with the firing gap of the spark plug, a tubular ceramic member having a high dielectric constant having direct contact with the outer peripheries of the discharge faces of the secondary electrodes to change thereby the predetermined air sparking space into a surface sparking gap, and a current-conducting member bonded to the external surface of said tubular ceramic member in a non-conductive relation to the secondary electrodes to thereby provide an electrically floating conducting member, said current-conducting member having a length dimensioned and arranged to bridge in a non-conductive relation the said surface sparking gap.

4. In a spark plug in combination, an insulator formed with a longitudinal bore, a main composite electrode comprising a plurality of components located within the bore of said insulator, the lower component of said composite electrode formed by a metallic section sealing the bore of said insulator with its end projecting therefrom, the upper component of said composite electrode formed by a hollow metallic member for subjecting the bore of said insulator to the atmosphere, secondary perforated electrodes having uniplanar discharge faces spaced apart in axial alignment to define a predetermined air sparking space subjected to atmosphere forming a sparking gap in series relation to the upper and lower sections of said composite electrode, a tubular

member of ceramic insulating material having a dielectric constant higher than air directly contacting the outer peripheries of said uniplanar discharge faces to change the said predetermined air sparking space into a surface sparking gap, and a current-conducting member positioned on the outer wall of said tubular member in non-conductive relation to both sections of the main electrode and separated from said secondary electrodes by the wall of said tubular insulating member, said current-conducting member dimensioned and arranged to bridge the predetermined space between the secondary electrodes and extend therebeyond to overlap a portion of the discharge faces of the secondary electrodes without direct electrical connection with the electrodes whereby said current-conducting member is electrically floating with respect to the main and secondary electrodes.
